THREAD ADVANCING REEL

Walter F. Knebusch, Rocky River, Ohio, assignor
to Industrial Rayon Corporation, Cleveland,
Ohio, a corporation of Delaware

Application January 26, 1938, Serial No. 186,980

10 Claims. (Cl. 242—53)

This invention relates to a novel form of winding reel of the type which is adapted, by the action of the elements thereof, to advance thread or the like lengthwise thereof in a plurality of substantially helical turns. More particularly, the invention relates to a reel of this type of cantilever form; that is, a reel which is supported and, if positively rotated, which is driven from one end only, having its other end unobstructed 10 by either supporting or driving means. The present application, which is directed per se to such a reel, is a continuation in part of copending application Serial No. 7,113, filed February 18, 1935.

The reel of the present invention has numerous far-reaching advantages, wherefore it is adapted to widespread application in industry. It may be employed to particularly great advantage in the continuous processing of thread or the like, such, for example, as artificial silk thread made 20 by any of the usual processes; e. g., the viscose, cuprammonium, nitrocellulose and cellulose acetate processes. For convenience, but in no sense of limitation, it will be described hereinafter in connection with the continuous processing of artificial silk thread and, in particular, in connection with the manufacture by a continuous process of multiple filament viscose artificial silk thread. It will be understood that it is equally adapted to the manufacture of any thread-like 25 article, whether of natural or synthetic origin.

In the manufacture of multiple filament viscose artificial silk thread, it has long been recognized that, if the most economical utilization of the manufacturing facilities is to be realized, the thread must be produced at a high speed. At the same time, in order adequately to process the thread, it is necessary that it be subjected to each processing medium for a considerable period of time, as much as and in some cases 35 more than half a minute under the most favorable conditions; i. e., where it is possible to carry out the processing operation with the thread in the form of a single thread rather than the form of a package. In these circumstances it was 40 early recognized that in any method of continuously processing viscose artificial silk thread it would be necessary to subject a great length of the thread to the action of the processing medium at one and the same time, this in order that the 45 thread might be sufficiently processed at the high speeds necessary to commercially practicable operation.

Nevertheless in order that the cost of the facilities be not rendered prohibitively high, it has 50 been and is imperative that such great length

of thread be processed in a very small space. It was soon appreciated, therefore, that the greatest possibilities lay in the direction of continuously but temporarily storing the thread, at least during the period of processing, in the form of 5 a travelling spiral consisting of a large number of generally helical turns. To that end, numerous attempts have been made to provide a satisfactory thread-advancing, thread store device, such prior devices having in general been of one 10 or two distinct types.

On one hand, prior devices of this sort have been formed of two or more widely separated members, at least one being rotatable, around both or all of which the thread has been wound 15 by hand in a plurality of generally helical turns. Examples are devices formed of spaced rotatable rollers disposed in inclined relation to each other; likewise, devices made up of a single rotatable drum and, spaced therefrom, a cooperating 20 hooked or notched member serving to keep the thread turns separated from each other. On the other hand, devices of this sort have taken the form of unitary winding reels made up of interdigitating sets of bar members cooperating to 25 advance the thread lengthwise of the reel.

Such prior devices have not been successful because of the great difficulties involved in threading them up; i. e., starting the thread thereon, as well as in transferring the leading 30 end of the thread from one device to another.

In the manufacture of viscose artificial silk thread, for example, it is necessary because of the large number of diversified processing operations which must be performed upon the thread to employ for each thread a considerable number of thread-advancing, thread store devices. Thus it has been found that as many as ten thread-advancing, thread store devices are needed to completely process each thread. Since several 40 thousands of threads must necessarily be produced simultaneously in a single plant in order to obtain the necessary production, the number of thread-advancing, thread store devices which must be employed in such a plant therefore approaches or exceeds one hundred thousand. From time to time all of such devices must be threaded up and the leading ends of the threads duly transferred from device to device.

While apparatus for the manufacture of viscose artificial silk thread by a continuous method may run for months at a time after having been completely threaded up, the individual thread-advancing, thread store devices must be 50

threaded up much more often than at first appears.

For one thing, all of the devices must all be threaded up and the leading ends of the threads must be transferred from device to device every time the machine as a whole is started up, representing a task of no small magnitude. Thereafter, whenever a thread is broken for any reason—and a certain amount of breakage is bound to occur—all devices in the series subsequent to the point of breakage must be threaded up, in connection with which the leading end of the thread must be transferred between each pair of adjacent devices. Whenever a spinneret, spinning pump or the like is cleaned, repaired or replaced—and in every plant a large number must be and are cleaned, repaired or replaced daily—the continuity of the thread must be interrupted with the same consequences. For such reasons, in a plant of even average size, it may be necessary to perform daily hundreds, if not actually thousands, of threading up and transferring operations.

The facility with which such operations can be performed necessarily affects to a very large extent the commercial failure or success of continuous processing apparatus.

Prior devices of the first of the two classes above indicated; i. e., those including one or more spaced rotatable members, are by no means easy to thread up; indeed, it is always difficult and in some cases impossible to thread them up other than manually. This arises from the fact that the thread, if brought into contact with the rotating member, simply winds about that member and, inasmuch as the leading end obviously cannot possibly pass from such rotating member to the other member without the aid of extraneous means, tends to accumulate thereon in a shapeless mass. Therefore, it is necessary to pass the leading end of the thread in the requisite number of turns by hand around all of the several members of the device. In order to process the requisite long length of thread a large number of turns must be stored on the device; e. g., from fifty to a hundred or more, in consequence of which fact the time required to thread up such a device by hand is so great as to render the general use of devices of this type utterly impractical.

Certain, but by no means all, of the prior devices of the second type; to wit, thread-advancing reels, have the advantage of being self-threading; that is, if the leading end of the thread is brought into contact with the rotating reel or wound once or twice around the reel, the reel will automatically wind the thread and advance it lengthwise thereof in a plurality of spaced substantially helical turns. It is with such devices; i. e., self-threading thread-advancing reels, rather than with devices of the first-mentioned type, that the present invention deals. Heretofore all of such thread-advancing reels have had both ends obstructed by driving means, supporting elements, etc., which have invariably impeded the free discharge of the thread from the reel.

In starting the thread on apparatus employing such double-ended reels it has been found necessary for the operator, after he has once started the thread on a given reel, to remain in close attendance in order to be ready to pick the leading end of the thread off the reel when such leading end reaches the intended discharge point. If he does not pick off the leading end of the

thread at the proper time, the thread will progress to the end of the reel, override the same, and entangle about the shaft, frame, etc. Due to the high rate of travel of the thread, the amount of such discharged and entangled thread will, if overriding is not prevented, grow large enough in a very short time to jam the reel, causing loss of production time if not, indeed, actual breakage of the reel.

Moreover, even if, as has been proposed, automatic transfer devices are employed with such prior reels, similar disadvantages are experienced, these disadvantages being in addition to the important disadvantage of considerably increased initial cost arising from the use of such transfer devices. With transfer devices, it is generally necessary to form a new leading end on the thread, this because of the fact that the original leading end is frequently disposed beneath one or more of the first few turns of thread. After the new leading end has been formed by the transfer device, the several turns of thread containing the old leading end continue to progress to the end of the reel, override the same, and are discharged therefrom, becoming entangled about the shaft, frame, etc., as previously described. Thus even in the case of apparatus equipped with transfer devices there is a very real possibility of breakage of the apparatus if the entangled thread is not promptly removed.

In either case, removal of the entangled thread and close attention on the part of the operator require so much time that, in the operation of apparatus employing such reels, labor costs are excessively high. Especially is this true in view of the large number of reels which must be employed and the large number of threading up and transfer operations which must necessarily be performed. To this difficult problem; to wit, economically threading up the large numbers of reels which must be employed in commercial practice and transferring the thread therebetween with a minimum of time and labor, the reel of the present invention provides the first satisfactory solution.

The features of the invention will be apparent from the following description taken with the accompanying drawings.

In the drawings, Figure 1 represents a sectional elevation through a reel embodying the present invention, the section through the reel being generally along line 1—1 of Figure 2. Figure 2 is an end elevation of said reel, corresponding to the left-hand end of Figure 1. Figure 3 is a detail sectional elevation of the illustrated reel along line 3—3 of Figure 1. Figure 4 is a perspective of a reel of the present invention showing the reel while it is temporarily continuously storing thread. Figure 5 is a perspective of a reel of the present invention showing the annular bundle of thread which under certain conditions forms at the end of the reel. Figure 6 is a side elevation of a portion of an apparatus for the continuous processing of thread embodying the reels of the present invention, the reels being shown diagrammatically. Figure 7 is an elevation from line 7—7 of Figure 6 of a portion of the front of said apparatus. Figure 8 is an elevation in perspective of a portion of said apparatus showing the relationship of the reels to each other. In the drawings, like reference numerals refer to like parts throughout.

An illustrative embodiment of a reel embraced by the present invention is shown in Figures 1, 2, 3, 4 and 5. Said reel comprises two wholly

rigid, generally cylindrical reel members 1 and 2. Reel member 1 has a thread-bearing periphery comprising a plurality of spaced longitudinally extending bar members 3, while reel member 2 has a thread-bearing periphery comprising a plurality of spaced longitudinally extending bar members 4. The bar members of the two reel members interdigitate, being alternately disposed. Each of the reel members is mounted for 10 rotation about its own axis, the axes of the two reel members being disposed in offset and inclined relation to each other in spaced parallel planes. The reel is mounted from one end only, having its other end unobstructed by supporting 15 means, driving means, etc.

In the illustrated reel, reel member 1 may be termed the concentric reel member, since it is mounted concentrically upon, fixed to, and adapted to rotate with drive shaft 5. It comprises a generally cylindrical hollow body portion 6 on which are rigidly mounted the bar members 3. The periphery of the body portion is slotted to form alternating bar members 3 and recesses 7, in which recesses are disposed the bar members 25 of the other reel member. The reel member is mounted on a sleeve 8 keyed to the shaft 5 and is held in place against a shoulder 9 on the drive shaft by means of a cap screw 10 threaded into the end of the shaft, the cap screw 10 passing 30 through and clamping in place an imperforate disc 11 which seats against and seals the corresponding beveled body portion 6. All portions of reel member 1 are immovable with respect to each other, so that there is obtained a strong, 35 rigid reel member.

The other member 2 may be termed the eccentric member, because while it is of generally cylindrical form and concentric with its axis of rotation, it is mounted with its axis slightly offset 40 from and inclined to the axis of drive shaft 5. The eccentric member 2, all parts of which are likewise immovable with respect to all other parts of said member, includes a head formed of inner ring 12 and outer ring 13, said 45 inner ring 12 having peripheral slots 14 adapted to receive the bar members 4. Rings 12 and 13 are respectively externally and internally tapered as shown, being held together by screws 15 (Figures 1 and 3). The bar members 4 are rigidly 50 clamped between the rings at one end thereof, said bar members projecting between the bar members 3 of the concentric reel member 1. The inner ring 12 has fixed therein a sleeve 16 by means of which eccentric reel member 2 is journaled on a supporting member 17 in the desired 55 offset and inclined relation.

The reel as a whole should preferably be of such design as not to be damaged by the processing media applied to the thread, which are often corrosive in nature. The reel members, or at least those parts which come into contact with corrosive reagents, are preferably made of such materials and in such manner as to be unaffected by the processing reagents. In the embodiment 60 shown, concentric member 1 is molded of hard rubber, Bakelite or similar material, being molded around or having rigidly fixed therein the central metal sleeve 8. The disc 11, which aids in clamping the concentric member 1 on the drive shaft 5, may also be made of or coated with hard rubber, Bakelite or similar material. Member 11 may be similarly made up of parts formed of hard rubber, Bakelite or similar materials. A flexible sealing sleeve or boot 18, which may be made of 65 rubber or like material, may be disposed between

the two reel members 1 and 2, as shown in Figure 1, to protect the bearings and other metal parts of the reel.

By such a construction, the reel may be supported and driven from one end only, leaving its other end substantially unobstructed.

The illustrated reel operated on the same principle as the reel shown, claimed and described in copending application Serial No. 652,089, filed January 16, 1933. The rotation of the drive shaft 10 causes concentric reel member 1 to rotate. Contact of the bar members 3 of said reel member 1 with the bar members 4 of eccentric reel member 2 causes said eccentric reel member to rotate about its own axis. Therefore, during operation 15 of the reel, both reel members rotate at the same angular speed, each about its own axis.

Because of the offset relationship of the axes of the two generally cylindrical reel members, each turn of thread on the reel is carried by both reel members, and, as the reel members rotate, the thread in each turn passes from one reel member to the other. The thread starting on each reel member winds on such reel member in a path at right angles to the axis of rotation of such reel member. Therefore, because the axes of rotation of the two members are inclined to each other, the thread in each turn which has left one reel member at a certain point longitudinally thereof to start on the other reel member subsequently starts again on said first-mentioned reel member at a point spaced longitudinally from the first-mentioned point thereon. In this manner the thread turns on the reel are caused to advance lengthwise thereof.

Since the reel comprises two generally cylindrical sets of interdigitating bar members, the peripheries of the reel members formed of said sets of bar members necessarily intersect.

Therefore, the reel is self-threading; that is, 40 if a thread is merely brought into contact with the reel as it is rotating or is at most wound about the reel once or twice, the thread will by the action of the reel member be caused to wind on the reel and form spaced generally helical turns 45 which advance lengthwise of the reel. If the thread has sufficient adherence to cause it to cling to the bar members of the reel, as is the case with wet thread, it need be only contacted with the rotating reel, whereupon it will be caused to form spaced generally cylindrical turns as the reel rotates. If the thread has not sufficient adherence to cling to the bar members when contacted therewith, as if the thread be dry, it need merely be wound about the reel once or twice in 50 order to secure a grip on the reel, after which it will be formed during rotation of the reel into the desired spaced generally helical turns.

The reel is self-threading because the intersection of the thread-bearing peripheries of the reel members prevents the leading end of the thread from being carried around only one reel member and thus piling up thereon and preventing advance of the thread. When the leading end of the thread reaches the intersection of the reel peripheries of the two reel members, it is picked up from the bar members of one reel member by those of the other reel member. This is in contradistinction to the action of prior devices formed of widely separated rollers, in which, as has been explained, if the leading end of the thread is brought into contact with one of such rollers it clings to only that member and winds around it.

In the illustrated reel, the amount of inclina- 75

tion of the axes of the reel members determines the amount that each thread turn advances during one revolution of the reel or, in other words, determines the pitch of the helix formed by the thread turns on the reel. In general, the greater the amount of such inclination, the greater the advance of the thread turns and hence the larger is the pitch of the helix. Under certain circumstances it may be desirable to provide for adjustment of the inclination between the axes of rotation of the two reel members. In the illustrated reel, for instance, supporting member 17, on which the eccentric reel member is mounted, is adapted to be adjustably positioned to vary the inclination of the axes of rotation of the reel members. The particular means for accomplishing this result forms no part of the present invention and therefore will not be described in detail herein but the illustrated adjusting means is the same as that shown, described and claimed in applicant's copending application Serial No. 7,116, filed February 18, 1935.

For a given direction of offset and a given direction of inclination of the axes of the reel members, the direction of rotation of the reel determines the direction of advance of the thread lengthwise of the reel. Similarly, for the same direction of offset and a given direction of rotation, the direction of inclination of the axes of the reel members determines the direction of advance of the thread. In general, it is preferable to so relate these factors that the thread is advanced toward the unsupported end of the reel, since in this manner the cantilever feature of the reel can be utilized to the greatest advantage. In the case of the illustrated reel, for instance, the thread turns may be advanced toward the unsupported end of the reel if the reel is rotated in clockwise direction when viewed from the unsupported end; that is, when the reel is rotated in the direction indicated by the arrow in Figures 2, 4 and 5.

The reel of the present invention has one end unsupported and has no drive shaft or other extension which prevents winding of thread over the unsupported end of the reel, which is extremely advantageous.

In the case of the illustrated reel, but a few seconds of the operator's time is required for starting the thread on the reel and transferring it to the succeeding reel. Because the reel is self-threading, it is merely necessary for the operator to bring the leading end of the thread into contact with the rotating reel or at most to wind the thread once or twice about the reel. Winding of the thread once or twice around the reel, as may be desirable to secure a good grip, may be more readily accomplished in view of the fact that the thread may be wound over the unsupported end of the reel, which cannot be done with double-ended reels. Thus in the case of the reel of the present invention the threading up operation is very simple indeed.

Because one end of the reel is substantially unobstructed, no harm occurs when the turns of thread are advanced to and beyond the unsupported end of the reel; rather, the thread simply discharges from the unsupported end of the reel. Therefore with the reel of the present invention, in contradistinction to prior double-ended reels, there is no need for the operator to remain in close attendance on the reel; after starting the thread on the reel, an operation requiring only a second or so, the operator can leave the reel to perform other tasks, as to thread

up other reels or to transfer a thread therebetween, etc. Since no harm can follow from the discharging of the thread from the unsupported end of the reel, the operator can return at his convenience to effect the transfer of the leading end of the thread to the succeeding reel.

To effect the transfer of the thread to the succeeding reel or device, it is merely necessary for the operator to break the discharged thread and pass the new leading end to the succeeding reel or device, an operation requiring only one or two seconds. The transfer of the thread to the succeeding reel or device is also facilitated by the fact that it is much easier to remove the thread from the unsupported end of the reel of the present invention than from the side of the reel, as is necessary with prior double-ended reels. For such reasons only a very small amount of the operator's time and labor is required to thread up each reel and transfer the thread therefrom. Efficient utilization of the operator's time is therefore possible, one operator being free to tend a much larger number of reels than would otherwise be the case.

The reel illustrated as embodying the invention possesses other important advantages which are not readily apparent.

It has been found that when the thread discharges from the unsupported end of the reel, which occurs when the thread is not being led away from the reel, such discharged thread will under suitable circumstances form either an annular bundle at the ends of the bar members at the unsupported end of the reel or a web of thread across the unsupported end of the reel, or, in some cases, a combination of the bundle and web. The annular bundle or web forms either (a) in the threading up operation after the thread has been started on the reel and the reel has been completely threaded up, but the thread has not been led away from the reel, or (b) when the thread or filaments thereof break. In the second case, when breakage of the thread or filaments thereof occurs after the thread has left a reel but before it starts on the succeeding reel, the annular bundle or web will form at the end of the first-mentioned reel.

Figure 4 shows in perspective a fully threaded up reel to which the thread 19 is passing and from which it is leaving, the direction of rotation of the reel and the direction of travel of the thread being indicated by the arrows. This condition obtains when the reel continuously temporarily stores the thread. Figure 5 shows in perspective a fully threaded up reel to which the thread is passing, but from which the thread is not being led, the direction of rotation of the reel and direction of travel of the thread to the reel being indicated by the arrows. In the case illustrated in this figure, the thread reaching the unsupported end of the reel forms an annular bundle 20 which clings to the ends of the bar members at such end of the reel.

The annular bundle of thread forms most effectively when the thread is wet, which is generally the case in continuous processing apparatus because the thread is wet by processing liquids. Such annular bundle apparently forms because of the adhesion of the discharged thread turns at the end of the reel to each other and to the reel. It has been observed that in the threading up operation when the leading turns of thread first reach the unsupported end of the reel, they do not discharge therefrom but cling to the reel. Succeeding thread turns in effect

pile up against such leading turns. In time a large annular bundle is formed, which if permitted to grow, eventually drops off the reel, after which another bundle begins to form. The bundle in no way entangles about any portions of the reel but drops entirely free of the reel when it leaves the reel.

The above-described annular bundle of thread will form at the unsupported end of the reel on a reel of the illustrated type; i. e., a reel formed of two rigid interdigitating sets of bar members which rotate about inclined axes, when the sets of bar members are of the same length at the unsupported end of the reel, as shown in Figure 1; that is, if the planes in which the ends of the bar members of the two sets lie intersect in a line which passes substantially through the center of the substantially circular open end of the reel. However, it has been found that the formation of the annular bundle is facilitated if the bar members of one of the reel members are made somewhat shorter than the bar members of the other reel member, that is, if the planes in which the ends of the bar members of the inclined reel members lie intersect in a line considerably removed from the center of the circular open end of the reel.

Under such circumstances the bar members of one set project somewhat beyond those of the other set at the unsupported end of the reel and therefore carry the thread alone at this portion of the reel. On the portion of the reel back of the unsupported end on which the thread is carried by the bar members of both sets, the thread is positively advanced by cooperation of the bar members of both sets. On the short portion of the reel adjacent the unsupported end on which the thread is carried by the bar members of only one set, the thread is not positively advanced but is merely gradually pushed forward in a more or less compact annular bundle by the action of the thread turns discharged from the portion of the reel on which the thread is supported by the bar members of both reel members. Thus the formation of the annular bundle is facilitated, particularly since it is possible for the projecting ends of the bar members of one of the sets to give better support to the annular bundle than under other circumstances.

An even more important advantage of the formation of an annular bundle or web at the unsupported end of the reel is that such bundle or web serves as an effective signal to warn the operator in the event of thread breakage.

The formation of the annular bundle is also advantageous in signaling the presence of broken filaments. For instance, if certain filaments of the thread should break between reels, such broken filaments will form a bundle or web at the unsupported end of the reel preceding the point of breakage; while if breakage of filaments should occur while the thread is on the reel, such broken filaments will collect in an annular bundle or web at the unsupported end of the reel on which such breakage occurred. Thus the presence of broken filaments in the artificial silk thread, which in ordinary artificial silk manufacturing practice cannot be detected until the thread is finished, is infallibly indicated by the reel of the present invention during the manufacturing process, when the factors causing such condition can readily and quickly be corrected.

In any event, whether breakage of the thread occurs or whether breakage of filaments occurs, the formation of such an annular bundle on the

reel is advantageous in acting as a quick, easily discernible signal to the operator.

Because of the cantilever construction of the reel of the present invention, it lends itself very well to use in novel and extremely advantageous forms of apparatus for the manufacture of thread by a continuous process or for the continuous processing of thread. A portion of one form of such apparatus in which the advantages of the reel of the present invention are utilized to the fullest extent is shown in Figures 6 and 7 and in perspective in Figure 8. The illustrated apparatus is of the general form as that shown, described and claimed in copending application Serial No. 7,114, filed February 18, 1935, by Walter F. Knebusch and Alden H. Burkholder for the "Manufacture of artificial silk."

As shown in the drawings, the machine comprises a plurality of descending series of reels each of which series comprises several reels 21, 21a, 21b, 21c, etc., disposed in processing sequence and by means of each of which series a single thread 19 from a suitable source, such as a spinneret disposed in a coagulating bath (not shown), is subjected to suitable or necessary processing treatments. The reels in the several descending series are disposed with their unsupported ends all extending in the same direction, corresponding reels in processing sequence in adjacent series being disposed in corresponding positions horizontally of the machine whereby constructional and operating advantages are obtained. The reels, moreover, are in the illustrated apparatus disposed in stepped arrangement, with the axes of all reels horizontal and with the unsupported end of each preceding reel in apposite relation to the supported end of each succeeding reel. Therefore the thread may pass directly from the unsupported or discharge end of each preceding reel to the supported or receiving end of the succeeding reel.

By reference to Figure 1, which shows a reel embodying the present invention mounted on a portion of the illustrated apparatus, it can be seen that in said apparatus the drive shaft 5 for the reel is journaled in the opposite walls of housing 22 which may extend longitudinally of the machine as shown in Figure 7 and serve to support several corresponding reels of adjacent series. The supporting member 17 for the reel is mounted on said housing. Each of the reels thus supported by the housing is driven from the drive shaft 23, extending longitudinally of the housing, through gears 24 and 25. In the illustrated embodiment the gear 25 is rotatably mounted on the drive shaft 5 of the reel and is adapted to be operatively connected thereto by a clutch marked generally 26. The drive shaft 23 for a plurality of reels disposed in horizontal series is adapted to be driven through change speed gears indicated generally by reference numeral 27 from a short shaft 28 on which is mounted a helical gear 29 meshing with a helical gear 30 mounted on a main drive shaft 32.

No means are shown for applying processing medium to the thread on reel 21, since it is intended that in the illustrated apparatus said reel be employed as a set-up or holding reel to provide a period of coagulation for the thread before it passes to the succeeding reels on which the thread is subjected to liquid processing treatment. The succeeding reels in the apparatus shown are provided with means for applying processing liquids to the thread and collecting such liquids. In the design shown, since corresponding reels in ad-

jacent processing series are disposed in corresponding positions longitudinally of the apparatus, each of the reels in each corresponding processing stage has mounted thereabove a suitable 5 reagent distributor 33 supplied through pipe 34 from a supply conduit 35 running horizontally of the machine. Below said reels disposed in corresponding positions horizontally of the apparatus is a collecting trough 36, which serves to collect the processing liquid after it leaves the reel. 10 Each of said collecting troughs communicates by suitable means with a common sewer or, if it is desired to re-use the processing liquid, with suitable recirculation and make-up means (not 15 shown).

The illustrated arrangement possesses numerous great advantages, most of which are made possible in a great degree by the reel of the present invention. In the first place, because of 20 the cantilever form of the reels, they may be advantageously disposed, as shown in the illustrated apparatus, in endwise relation to the operating face of the machine, with their unsupported ends all presented to the operator. By this arrangement 25 a very much more compact apparatus is made possible than can be obtained with other arrangements of the reels. This is very important in that it results in a low cost of construction of the apparatus, low plant space requirements, and makes possible less movement of the operator about the apparatus, thus increasing 30 labor efficiency in this respect.

What is even more important is the fact that the arrangement of reels in the illustrated apparatus 35 provides great accessibility and visibility of the reels to the operator.

Because the reels are disposed with their unsupported ends all extending in one direction toward the operator, they are very easily accessible 40 and visible to him for manipulation of the thread thereon, as for starting the thread on the reels and transferring the thread thereto, inspection, etc. The accessibility and visibility of the reels are increased because the reels are disposed in 45 stepped arrangement. The accessibility of the reels for operating purposes and the visibility of the reels in apparatus of the type illustrated are demonstrated to good advantage in Figure 8, which is a perspective elevation of a portion of 50 the apparatus showing several descending series of reels. As is apparent from this figure, in the fronts, tops and a good portion of the sides of all reels are easily accessible to the operator and clearly visible to him. In starting the thread on 55 a reel it is therefore a simple matter for the operator to contact the thread near the supported end of the reel or to wind it around the reel one or more times over the unsupported end of the reel, while in subsequently transferring the 60 thread from the reel after it is threaded up it is equally simple for him to pick off the thread from the unsupported end of the reel, form a new leading end and lead it to the succeeding reel or device. There is no need for the operator to 65 reach around or between shafts, as is necessary in apparatus employing the prior double-ended reels.

Figure 8 also illustrates how effectively the reels of the present invention can indicate when they are completely threaded up, or when breakage 70 of the thread has occurred, by means of the formation of the annular bundle or web of thread at the unsupported end of the reel. In Figure 8 annular bundles 20 are formed at the unsupported ends of the reels indicated by the letters A, B 75 and C, such bundles indicating either that each of

these reels is completely threaded up or that the thread has broken. In either event, such annular bundles form very noticeable signals to the operator that the thread should be transferred from such reels to the next succeeding reels A', B'. As 5 is apparent from this figure, even if the operator is a considerable distance away, he can tell at a glance the condition of the thread on all reels. It is further apparent from this illustration that even though it might be inconvenient for the operator to return immediately to complete the transfer of the thread, no harm will be done, since when the bundles grow to a certain size they merely drop off the supported end of the reels into the troughs and other bundles proceed to form, 10 such operations continuing until the operator returns to transfer the thread. 15

Moreover, when the cantilever reels of the present invention are disposed in an arrangement where-in the unsupported or discharge end of each preceding reel is disposed in apposite relation to the supported or receiving end of the succeeding reel, as is the case in the illustrated arrangement, under suitable conditions, as with certain kinds 20 of thread, suitable speeds of rotation, etc., transfer of the thread from a preceding reel to a succeeding reel may under suitable conditions be effected automatically. That is, in the threading up operation, when the thread reaches the unsupported end of a preceding reel it will be discharged therefrom and be dropped off or flung off into engagement with the succeeding reel. Since the reels are self-threading, such contact 25 will cause the thread to be wound about the succeeding reel in a plurality of helical turns which are advanced toward the unsupported end thereof and discharged, after which the operation may be 30 repeated until all reels are threaded up. This is an advantage which cannot possibly be provided by any prior thread-advancing, thread 35 store devices. 40

From the above discussion it is apparent that the reel of the present invention makes possible the complete solution of the threading-up and thread transfer problems which have heretofore 45 blocked development of a commercially practicable apparatus for the manufacture of artificial silk thread by a continuous process. Whereas in the past threading up and transferring the thread from prior thread-storage, thread-ad- 50 vancing devices has required commercially impracticable lengths of time, by means of the apparatus of the present invention such operations may be performed in only a very few seconds, an advantage of extreme importance in view of the 55 large number of thread-storage, thread-advancing devices which must necessarily be employed in manufacturing artificial silk thread, particularly viscose thread by a continuous process. Furthermore, as explained, the reel of the present 60 invention lends itself advantageously to various types of automatic transfer of the thread. 65

While the reel of the present invention has been discussed in connection with the manufacture of viscose artificial silk thread by a continuous 70 process, it is obviously not limited to such use alone, but may be employed in the continuous processing of any kind of thread, and, indeed, for various other uses than thread processing. For instance, materials other than thread may be advantageously wound on the reel, and it is intended 75 that in the appended claims the term "thread" should include, besides thread, all materials capable of being wound and advanced on a reel of the type to which the invention pertains. It 80

is apparent that various modifications may be made in the illustrated embodiment of the invention without departing from the spirit of the invention, and that the reel of the present invention is not necessarily restricted to employment in apparatus of the type illustrated.

It is intended that the patent shall cover, by suitable expression in the appended claims, whatever features of patentable novelty reside in the invention.

What is claimed is:

1. A thread-advancing reel of cantilever form comprising spaced, longitudinally extending bar members disposed around the thread-bearing periphery of the reel; means causing relative movement of said bar members during rotation of the reel to cause them to cooperate to advance in a plurality of generally helical turns thread wound on the reel; and means for supporting said reel from one end only thereof, the ends of the bar members at the unsupported end of the reel being unobstructed by anything impeding the free discharge of the thread.
2. A thread-advancing reel of cantilever form comprising two rotatable reel members mounted for rotation about independent axes in such relation to each other that the periphery of each reel member intersects that of the other reel member which reel members cooperate during rotation of the reel to advance in a plurality of generally helical turns thread wound on the reel, and, associated therewith, means for supporting said reel from one end only thereof, the ends of the reel members at the unsupported end of the reel being unobstructed by anything impeding the free discharge of the thread.
3. A thread-advancing reel of cantilever form comprising a first set of spaced, longitudinally extending bar members, a second set of spaced, longitudinally extending bar members alternating with those of said first set, said sets of bar members cooperating during rotation of the reel to advance in a plurality of generally helical turns thread wound on the reel, and means supporting said sets of bar members from one end only of the reel, the other end of the reel being left entirely unsupported.
4. A thread-advancing reel of cantilever form comprising a first set of longitudinally extending bar members arranged at intervals about the periphery of the reel, a second set of longitudinally extending bar members alternating with those of said first set, the bar members of said sets having limited relative but common rotary movement during rotation of the reel, and means supporting said sets of bar members from one end only of the reel, the other end of the reel being left entirely unsupported.
5. A thread-advancing reel of cantilever form comprising a bearing; a shaft projecting through said bearing, the projecting end of said shaft being wholly unsupported; two sets of interdigitating bar members mounted about and driven by said shaft, the ends of said sets of bar members at the unsupported end of said shaft being unobstructed by anything impeding the free discharge of thread from the reel; and means for

rotating said shaft in a direction such as to advance the thread along said sets of bar members toward the unobstructed ends thereof.

6. A thread-advancing reel of cantilever form comprising a first rigid set of spaced, longitudinally extending bar members, a second rigid set of spaced, longitudinally extending bar members alternating with those of said first set, the axes of said sets of bar members being in inclined relation to each other, and means supporting said sets of bar members from one end only of the reel, the other end of the reel being left entirely unsupported.

7. A thread-advancing reel of cantilever form comprising a frame member; a shaft projecting from said frame member, the projecting end of said shaft being wholly unsupported; a first rigid set of bar members concentrically mounted upon said shaft; and a second rigid set of bar members alternating with those of said first set eccentrically mounted on said frame member for rotation about an axis offset from that of said shaft, one end of the structure defined by said sets of bar members being unobstructed by anything impeding the free discharge of thread from the reel.

8. A thread-advancing reel of cantilever form comprising spaced, longitudinally extending bar members disposed around the thread-bearing periphery thereof; means causing relative movement of said bar members during rotation of the reel to cause them to cooperate to advance in a plurality of generally helical turns thread wound on the reel; and means for supporting said reel from one end thereof only in such manner that the ends of the bar members at the unsupported end of the reel are unobstructed by anything impeding the free discharge of the thread, said reel including means for forming a thread bundle at the unsupported end thereof.

9. A thread-advancing reel of cantilever form comprising two sets of spaced, longitudinally extending bar members disposed around the thread-bearing periphery thereof; means causing relative movement of said bar members during rotation of the reel to cause them to cooperate to advance in a plurality of generally helical turns thread wound on the reel; and means for supporting said reel from one end thereof only in such manner that the ends of the bar members at the unsupported end of the reel are unobstructed by anything impeding the free discharge of the thread, one of said sets of bar members extending beyond the other at the unsupported end of the reel.

10. A thread-advancing reel of cantilever form comprising spaced, longitudinally extending bar members disposed around the thread-bearing periphery thereof; means causing relative movement of said bar members during rotation of the reel to cause them to cooperate to advance in a plurality of generally helical turns thread wound on the reel; and means for supporting said reel from one end thereof only, the other end of the reel being left entirely unsupported.

WALTER F. KNEBUSCH.

CERTIFICATE OF CORRECTION.

Patent No. 2,210,911.

August 13, 1940.

WALTER F. KNEBUSCH.

It is hereby certified that error appears in the printed specification of the above numbered patent requiring correction as follows: Page 3, second column, line 7, for the word "operated" read --operates--; page 6, second column, line 14, for "supported" read --unsupported--; and that the said Letters Patent should be read with this correction therein that the same may conform to the record of the case in the Patent Office.

Signed and sealed this 22nd day of October, A. D. 1940.

(Seal)

Henry Van Arsdale,
Acting Commissioner of Patents.
